UNITED STATES PATENT OFFICE.

HOWARD B. ROBINSON, OF HARTFORD, CONNECTICUT.

CLEANER FOR MOVING-PICTURE FILMS.

1,199,424.

Specification of Letters Patent. Patented Sept. 26, 1916.

Application filed October 29, 1913. Serial No. 798,153.

To all whom it may concern:

Be it known that I, HOWARD B. ROBINSON, a citizen of the United States, residing at Hartford, in the county of Hartford and 5 State of Connecticut, have invented certain new and useful Improvements in Cleaners for Moving-Picture Films, of which the following is a specification.

This invention relates to cleaners for moving-picture films, the object of the invention being to provide a device of this character which is simple in construction, which can be readily and easily operated, and by which a film or equivalent, can be effectually and 15 thoroughly cleaned.

The invention includes other features of novelty and advantage, which with the foregoing will be stated at length in the following description, wherein I will set forth that 20 one of the several embodiments of the invention which I have selected for illustration in the drawings accompanying and forming part of the present specification. I do not limit myself to this disclosure; I may 25 depart therefrom in several respects within the scope of the invention defined by the claims following said description.

Referring to said drawings: Figure 1 is a 30 vertical transverse section of a cleaner involving my invention. Fig. 2 is a side elevation of the same, showing a portion of a moving-picture machine. Fig. 3 is a transverse section of a cleaning roller.

Like characters refer to like parts in the 35 several figures.

The different parts of my cleaner may be supported by any suitable framework. The framework shown includes in its make-up the duplicate side-members 2 connected near 40 their tops by the cross piece 3. Said side members 2 are shown provided with in-turned feet 4 connected by rivets or otherwise, with the base member 5 which as shown is supported for sliding movement by the 45 plate 6 having guide ways to receive said base member, so that the frame as a whole with the parts thereon, can be moved toward and from the receiving reel of a motion-picture machine to adjust the tension of a belt 50 or band hereinafter described, provided such a band is utilized to transfer power. This plate 6 is fastened to some suitable rigid part of the moving-picture machine and into it is tapped the screw 7, the base member 5 having a slot 8 elongated in a direction 55 transversely thereof to receive said screw 7,

the head of which is adapted to engage against the upper surface of the base member to hold the framing and the parts connected therewith, in an adjusted position. 60 By loosening the screw 7 the framing can be adjusted to move it toward or from the receiving or take-up reel 9 of the moving-picture machine onto which the film 10 is received from the companion reel (not 65 shown.) The cleaner is disposed between the two reels mentioned, the film being cleaned thereby in its movement from one to the other of said reels.

I have described a framework which is 70 suitable for sustaining the different parts of the device and which is adjustable. As will be inferred from what I have already noted a framework of an entirely different character without such an adjustment may be 75 provided.

The cleaning mechanism in the present case consists of superimposed rollers as 11 and 12, the peripheries of which are preferably soft so as not to mar or injure the film. 80 This particular condition can be secured in a variety of ways, although one of an advantageous character will be hereinafter set forth. Said rollers 11 and 12 are as shown, connected together for simultaneous rotation, for instance by being geared together, their shafts as illustrated, being equipped with meshing spur-gears 13 and 14 fastened to the bodies of the rollers or drums in any convenient manner for instance by several 85 screws. The shaft of the upper roller 12 is supported directly by the side members 2. The lower shaft 11 extends through arcuate slots in the side bars 2 and its journal portions are sustained by the short branches of 90 angle levers 15 supported at their elbows on the outer sides of the side members 2. Connected with the longer branches of the said levers 15 and also with the side bars 2 are the pull springs 16 which yieldingly urge 95 the lower roller 11 toward the companion roller 12. The upper roller 12 is connected in some suitable way with the take-up reel 9. For instance said take-up reel as shown is 100 furnished with a band wheel 17 rotary therewith and connected by a band 18 with the small band wheel 19 fast to the shaft of the upper roller 12, so that when the take-up or receiving reel is turned by the hand crank 20 or otherwise, to wind the film 10 thereon, 105 the two rollers 11 and 12 through the described connections will be simultaneously 110

rotated to cause their soft peripheries to wipe the opposite faces of the film 10 being fed therebetween. The two rollers 11 and 12 rotate oppositely and in a direction opposite to the line of movement of the film 10 in order to facilitate the cleaning action.

The bodies or cores of the two rollers 11 and 12 can be clothed in any desirable manner, to obtain the soft or yielding peripheries to 10 which I have referred, for instance by strips of felt 21 attached at one end of each to its roller by a wedge piece 22 driven into a wedge channel or groove 23 extending longitudinally of the cores of the respective 15 rollers, the strips of felt 21 being wrapped about the respective rollers in a direction opposite their direction of rotation (Fig. 3) to prevent accidental unwinding of the strips. This also provides for the very easy 20 way of removing the felt strips which are attached to the rollers at only one end thereof. The width of each strip is about equal to the length of the core around which it is wound. The length of said strips is a 25 little more than twice the circumference of the cores or bodies of the respective rollers, by reason of which there are practically four independent cleaning areas or portions presented by each strip. That is to say each 30 strip can be reversed with respect to its faces and also with respect to its ends.

In the operation of a moving-picture machine the film is unwound from the primary reel and is passed between the rollers or 35 drums 11 and 12 and is then connected with the receiving or take-up reel 9. When the reel 9 is turned in the manner already described the film 10 is moved and at the same time the two rollers 11 and 12 are simultaneously rotated to perform their cleaning 40 offices. To aid in an understanding of the operation I have shown by arrows in Fig. 2 the direction of movement of the parts.

I provide means of a positive nature for 45 preventing the film being cleaned and the felt pads 21 from getting into the teeth of the intermeshing gears 13 and 14. The

guard 24 answers satisfactorily in this connection. This guard is shown consisting of a plate or disk fitted against the core of the 50 upper roller 12 and engaged on its outer side by the gear 14, the screws which hold said gear in place being utilized to fasten said guard in position. The diameter of this guard is greater than that of the core 55 of the upper roller 12, and its outer edge extends into an annular rabbet or groove 25 in the lower roller 11 in order to secure the functions in question.

What I claim is:

1. In a cleaner for moving picture films, a pair of cleaning rollers geared together for opposite rotation, the peripheries of the rollers being soft and being adapted to receive between them a moving picture film, said 60 peripheries consisting of strips of textile material wrapped about the cores of said rollers in a direction opposite to their respective movements, said strips being unfastened at the outer edges whereby they 65 may be unwound and reversed.

2. In a cleaner for moving picture films, a roller, frame members supporting the roller for rotation, a second roller geared to the first roller for rotation in a direction 70 opposite to that of the first roller, the second roller having a shaft and the frame members having slots through which the ends of 75 said shaft extend, angle levers supported at their angles for oscillation on the outside of 80 said frame members, one branch of each of the levers receiving for rotation an adjacent projecting end of said shaft, and springs 85 connected with the frame members and with the other branches of said levers for yieldingly urging the second roller toward the first roller, the peripheries of the two rollers being soft.

In testimony whereof I affix my signature in presence of two witnesses.

HOWARD B. ROBINSON.
